(57) **CLAIM**

The ornamental design for a hand shield for a gun, as shown and described.

DESCRIPTION

FIG. 1 is a perspective view of the first embodiment of a hand shield for a gun showing the new design attached to an unclaimed pistol grip;

FIG. 2 is another perspective view of the embodiment from FIG. 1;

FIG. 3 is a front side elevational view of the embodiment from FIG. 1;

FIG. 4 is a back side elevational view of the embodiment from FIG. 1;

FIG. 5 is a right side elevational view of the embodiment from FIG. 1;

FIG. 6 is a left side elevational view of the embodiment from FIG. 1;

FIG. 7 is a top plan view of the embodiment from FIG. 1.

FIG. 8 is a bottom plan view of the embodiment from FIG. 1.

FIG. 9 is a front perspective view of the second embodiment of a hand shield for a gun attached to an unclaimed pistol grip and showing the new design with an unclaimed zipper;

FIG. 10 is a back perspective view of the embodiment from FIG. 9;

FIG. 11 is a front side elevational view of the embodiment from FIG. 9;

FIG. 12 is a back side elevational view of the embodiment from FIG. 9;

FIG. 13 is a right side elevational view of the embodiment from FIG. 9;

FIG. 14 is a left side elevational view of the embodiment from FIG. 9;

FIG. 15 is a top plan view of the embodiment from FIG. 9;

and,
FIG. 16 is a bottom plan view of the embodiment from FIG. 9.

The broken lines showing of the pistol grip in FIGS. 1 and 9 and the zipper in FIGS. 9-14 and 16 are included for the purpose of illustrating environment and form no part of the claimed design. The broken lines that follow the periphery of the hand shield in FIGS. 1 through 4 and 9 through 12 represents stitching and forms no part of the claimed design.
